UNITED STATES PATENT OFFICE.

ARTEMAS E. COLBURN, OF BELLINGHAM, WASHINGTON.

DESIGN FOR A PIN OR BROOCH.

No. 38,705.

Specification for Design.

Patented July 30, 1907.

Application filed May 28, 1907. Serial No. 376,215. Term of patent 7 years.

To all whom it may concern:

Be it known that I, ARTEMAS E. COLBURN, a citizen of the United States, residing at Bellingham, in the county of Whatcom and State of Washington, have invented a new, original, and ornamental Design for a Pin or Brooch, of which the following is a specification, reference being had to the accompanying drawing, forming a part thereof.

The figure is a plan view of a pin or brooch embodying my new design.

I claim:

The ornamental design for a pin or brooch as shown.

ARTEMAS E. COLBURN.

Witnesses:

P. M. LIDDY,

A. H. FRASIER.
